UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

SWITCH HANDLE.

Application filed March 31, 1921. Serial No. 457,438.

My invention relates to electric switch handles, and particularly to a rotary snap switch handle. The object of my invention is to provide a handle of improved construction affording a one-way operating connection with the switch mechanism.

In the accompanying drawings—

Fig. 1 is a plan of a rotary snap switch to which a handle embodying my invention 10 in one form is applied;

Fig. 2 is a side elevation thereof;

Fig. 3 is a section through the handle drawn to an enlarged scale;

Figs. 4 and 5 are sections on the lines 15 4—4 and 5—5, Fig. 3, respectively.

Fig. 6 is a view corresponding to Fig. 5, but showing the handle in different position;

Fig. 7 is a perspective of a detail of construction; and

20 Fig. 8 is a broken plan of a modified construction.

In rotary snap switches, it is common to provide a switch mechanism which is rotatable in only one direction. In order to 25 obviate the danger of injury to the mechanism, should the operating handle be forced in a direction opposite to that in which the mechanism is designed to rotate, it has heretofore been proposed to provide a one-way 30 operating connection between the handle and the switch spindle. The constructions used for this purpose, however, have been more or less expensive to manufacture. The present invention provides a handle of this 35 type, which is rugged and substantial in construction, while at the same time economically manufactured and assembled, and efficient in operation.

A switch of the rotary snap type is shown 40 in Figs. 1 and 2, and comprises an insulating base 10, upon which a snap switch mechanism (not shown) of any suitable sort is mounted on the rotary operating spindle 11 (Fig. 3), the upper end of which projects through the 45 cover 12. The latter rests on the shoulder 13 of the base and is held against rotation by a boss 14 on the latter engaging a notch 15 in the side of the cover. The operating handle 16, to which my invention particularly 50 relates, carries a ferrule 17 tapped to screw upon the upper end of the spindle 11 as usual.

In the particular form of construction shown in Figs. 1 to 7 inclusive, a rectangular

chamber 18 is molded in the handle, and a 55 hole 19 opened thereto, through which access may be had to the outer end of the ferrule 17, for a purpose hereinafter mentioned. At its opposite end the chamber 18 is enlarged to form a bay 20, with which communicates a bayonet slot channel 21 to receive a ferrule retaining washer 22, after the fashion set forth in the Gates Patent No. 1,166,345, dated December 28, 1915.

The ferrule 17 is provided at its outer end 60 with a head 23 adapted to freely enter and rotate in the rectangular chamber 18. A gap 24 cut in the side of this head, accommodates the ratchet dog 25 pivoted on a pin 26. Surrounding the pin is a coil spring 27, one leg, 65 28, of which lies against the side of the gap 24, while its other leg, 29, bears against the side of the dog and tends constantly to force it outward against the walls of the chamber 18. The pin 26 is located eccentric to the 70 axis of the ferrule 17, so that while the dog 25 is pressed into the gap 24 when the handle 16 is rotated contra-clockwise with respect to the ferrule (see Fig. 6), and the handle turns freely thereon, yet when the handle 16 is rotated clockwise, (that is to say in the direction to operate the switch mechanism on the spindle 11) the nose of the dog engages one of the walls of the rectangular 75 chamber 18 and acting as a strut, imparts the rotary movement of the switch handle to the spindle 11. Thus while the handle 16 may be freely rotated in one direction, it positively operates the switch when rotated in 80 the opposite direction.

Interposed between the head 23 of the ferrule and the retaining washer 22, is a coil spring 30 which serves to press the handle 16 firmly down upon the cover 12 when the ferrule is screwed upon the spindle 11. The cover is thus firmly retained in seated position upon the base 10 in a manner well understood in the art. A washer, or washers, 85 31 may be arranged on the shank of the ferrule between the cover and the bearing boss 32 of the switch handle to take up wear between the parts. It is obvious that the relative longitudinal displacement of the ferrule in the handle incident to the screwing of the latter in the spindle, does not affect the operation of the ratchet dog in any way.

Inasmuch as the handle 16 is freely rotatable contra-clockwise on the ferrule, it is

obvious that some means must be afforded to engage the latter should it be desired to unscrew the handle from the spindle 11. For this purpose a cross slot 33 is formed in its head 23, and this cross slot is accessible through the hole 19 in the handle, so that it may be readily engaged by the end of a screw driver.

The construction just described is appropriate for handles of any suitable insulating material having sufficient mechanical strength to withstand the repeated action of the dog without injurious wear. Where the handle is made of soft material, however, such as rubber or insulating composition, I prefer to embed or force therein a metallic lining 34 for the rectangular chamber, as is indicated in Fig. 8. The dog 25 will then bear upon this metallic lining and cooperate therewith in precisely the same fashion as in the construction first described. In fact, the lining piece may be used in a porcelain handle if desired.

The particular construction of the dog 29, or the way in which it is mounted upon the ferrule 17, is subject to various modifications, as are also the other details of construction shown which constitute merely an illustrative embodiment of what I claim as my invention.

I claim—

1. A switch handle comprising a chambered body, a ferrule rotatable in said chambered body, and a ratchet dog pivotally mounted on said ferrule and having a one-way operating engagement directly with said body.

2. A switch handle comprising a chambered body, a ferrule rotatable in said chambered body, and a ratchet dog pivotally mounted on said ferrule eccentric to the axis of the latter, and having a one-way operating engagement directly with said body.

3. A switch handle comprising a body recessed to afford a non-circular chamber, a ferrule rotatable therein, and means pivoted to said ferrule having a one-way operating engagement with the walls of said chamber.

4. A switch handle having a chambered body, a ferrule rotatable therein, a gapped head for said ferrule, and a ratchet dog

arranged in said gap and having a one-way engagement with the body of the handle.

5. A switch handle having a chambered body, a ferrule rotarily and longitudinally displaceable in said handle, and means pivoted to said ferrule and operated to afford a one-way engagement between the ferrule and the body regardless of the relative longitudinal displacement of the parts.

6. A switch handle having a chambered body affording internal lateral bearing surfaces, a ferrule rotatable in said chambered body, and means pivoted to said ferrule affording a one-way operative connection between said ferrule and said lateral bearing surfaces.

7. A switch handle comprising a chambered body, a ferrule secured to said body and rotatable with respect thereto, said ferrule being screw threaded to afford a one-way connection with an associated switch spindle, together with a ratchet member pivoted on the ferrule eccentric to the axis of the latter and having a one-way operative engagement with the handle body, such engagement being effective on the rotation of the handle in the same direction as that necessary in order to effect the screw connection between the ferrule and the switch spindle.

8. A switch handle comprising a chambered body, a ferrule secured to said body and rotatable with respect thereto, said ferrule being screw threaded to afford a one-way connection with an associated switch spindle, together with a ratchet member pivoted on the ferrule eccentric to the axis of the latter and having a one-way operative engagement with the handle body, such engagement being effective on the rotation of the handle in the same direction as that necessary in order to effect the screw connection between the ferrule and the switch spindle, said handle being pierced to afford access to the ferrule for rotating the latter in the direction of the slip of the ratchet with respect to the handle, for the purpose of freeing the ferrule from the spindle.

In testimony whereof I have signed my name to this specification.

ARVID H. NERO.
